UNITED STATES PATENT OFFICE

PETER E. BURNS, OF SYRACUSE, NEW YORK, ASSIGNOR TO PASS & SEYMOUR, INC., OF SYRACUSE, NEW YORK, A CORPORATION OF NEW YORK

CONVENIENCE OUTLET FOR CANOPIES

Application filed January 11, 1928. Serial No. 246,048.

This invention relates to convenience outlets and more particularly to convenience outlets for use with fixture canopies formed of moulded insulating material.

5 It is a general object of the present invention to provide a novel and improved type of convenience outlet for use with canopies formed of moulded insulating material such as porcelain or the like.

10 One of the features of the invention consists in attaching the various parts of the convenience outlet to the canopy without securing any metal parts in the insulation parts by moulding or the like and without unduly complicating the moulding operation.

15 Another feature of the invention consists in arranging the contacts in recesses in the back of the canopy and covering these contacts with a block of insulating material held against displacement by engagement with parts on the canopy.

20 A further feature of the invention consists in the arrangement of the attachment plug 25 blade openings and of overhanging interlocking portions on the canopy in such positions that the moulding operation results in the formation of these openings and the under sides of the overhanging portions by the use 30 of single easily withdrawable cores.

35 Other and further features and objects of the invention resulting in simplicity of form and ease of manufacture will be apparent to those skilled in the art upon a consideration of the accompanying drawing and following specification, wherein is disclosed a single exemplary embodiment of the invention, with the understanding however that various changes may be made therein such as fall 40 within the scope of the appended claims without departing from the spirit of the invention.

In said drawing:

45 Fig. 1 is a rear elevation of a side wall bracket canopy provided with a convenience outlet, constructed according to the present invention;

50 Fig. 2 is a view similar to Fig. 1 on a larger scale, of that portion of the canopy which includes the convenience outlet, showing the insulating cover block removed;

Fig. 3 is a vertical section on line 3—3 of Fig. 1 showing the manner of retaining the block in position;

Fig. 4 is a vertical section on line 4—4 of Fig. 1; and,

Fig. 5 is a horizontal section on line 5—5 of Fig. 1.

When fixtures such as side wall brackets and the like are formed of insulating material, for instance moulded porcelain, it is sometimes difficult to attach parts, owing to the characteristics of the material. Particularly is this true when it is not desirable to have the fastening means show on the front of the canopy. Such moulded materials as porcelain do not readily permit of the insertion of metal parts during the moulding, which parts can be threaded to receive screws or other fastening means. Hence the present invention has for its object not only the elimination of visible fastening means from the front side of the canopy, but the provision of a means for attaching convenience outlet parts without the use of such visible fastening means.

Referring to the drawing, it will be seen that the invention is disclosed by way of example, in combination with a side wall bracket having an extremely shallow, substantially flat canopy 10, having the rearwardly extending peripheral flange 11 adapted to rest against a wall surface when the canopy is mounted. Near the lower end of the canopy, which is disclosed as elliptical, the flange 11 is widened as shown at 12 and there is an upward projection above this widened portion forming a platform 13 extending above the rear surface of the main portion of the canopy. From the front of the canopy a pair of spaced, plug-blade openings 14 extend through to the back of the canopy and are adapted to receive the blades of the conventional attachment plug, and are for this purpose properly spaced and sized to receive such blades.

In order to provide contact means to connect with the plug blades, a recess 15 is provided at the rear end of each opening 14, and these recesses are shaped to accommodate not only the contact springs 16, but the ends of

their terminal wires 17, and the stop washers 18 that serve to assist in retaining the contacts in position. In general configuration the recesses 15 are rectangular, being enlarged 5 at 19 and 20. The openings 14 enter substantially the longitudinal centers of the recesses 15, so that the ends of the bottom walls of the recesses 15 serve as supports for the lower edges of the contact springs 16. The depth 10 of these recesses is substantially equivalent to the width of the contact springs. Each contact member is of spring metal, bowed longitudinally as shown in Fig. 2 and provided on its front or forwardly projecting 15 edge at the center thereof with a guide tab 21 bent in the direction of the plane of the ends of the bowed portion. Each guide tab is given room for movement in the widened portion 22 of the opening 14, since it projects 20 forwardly of the normal front edge of the contact spring and hence out of the recess 15.

The outer surface of the lower portion of the platform 13 is bounded at the sides by portions 23 of the flange 11, which are just spaced apart the distance between the outer sides of the openings 14. The parts 23 are connected together at the bottom by part 24 so that there is in effect a three sided recess 25 above the platform formed between the parts 23, 23 and 24 and the back and top of this recess are open. This recess or pocket is adapted to be filled by a block of insulating material which has a portion protruding out over the platform beyond the recess. The 30 purpose of this block of insulating material is to completely cover the conducting parts of the contact springs and to retain them in position mechanically. The block of insulating material 25 is generally T-shaped, with 35 the head 26 of the T covering the portions of the contacts and parts of their terminal wires which are out beyond the flange portions 23, whereas the leg or center member 27 of the T fills up the recess formed by the parts 23, 23, 40 24 and rests over the recesses 15 to retain the contacts therein. The under surface of the leg 27 is provided with a pair of notches 29 forming extensions of the openings 14, when the block is in position, to accommodate any 45 portions of the plug blades which may pass by the contact springs. It will be seen from Fig. 5 that the contact blades pass on the outer sides of the contact springs and tend to reduce the amount of bow of these springs by 50 pushing them toward each other, thus not placing any undue strain on the separating wall 30 between them since the pressures against this wall are balanced. Of course any attempted movement of the contacts out of 55 their recesses is prevented by the bottom surface of block 25.

To retain this block in position so that it is readily removable, a pair of overhanging lugs or fingers 32 project toward each other, 60 over the recess, from parts 23 of the canopy

flange. These lugs are best shown in Figs. 1, 2 and 5. The center portion or leg 27 of the insulation block 25 has its outer edges re-entrant as shown at 33, so as to easily pass beneath these lugs 32 when the block is slid 70 into position with its lower surface sliding on the surface of the platform 13. The center leg enters the recess formed by the parts 23, 24, and is prevented from moving too far in the downward direction, as shown in Fig. 1, by engagement of the T-head with the parts 23 and the end of the center leg with the part 24. This engagement and that of the re-entrant surfaces of the center leg with the overhanging lugs 32 is normally sufficient to 75 retain the block in position, since any strain on the same resulting from inserting the attachment plug is a direct thrust against the lugs and there is no reason why the block 80 should be urged out of the recess. 85

To insure that the block 25 always remains in position, and particularly while being shipped when it is not mounted in a vertical position, means are provided to engage both the block and the canopy structure to retain the block in position. Conveniently this means comprises a simple screw and nut. The screw 34 is adapted to pass through the hole 35 in the center of the leg 27 of the insulating block and the head of the screw may be received in a counter-sunk recess 36 on the outer face of the block. The bottom of the hole 35 is enlarged as at 37 and is preferably non-circular to accommodate the correspondingly shaped nut 38, which is thus prevented from rotation in the hole. The nut is threaded to receive the shank of the screw 39. The length of the screw is such that when it is fully screwed into position the inner end projects beyond the bottom face of the block 100 25 as shown at 40 in Fig. 3 and is adapted to be received in a hole or recess 41 in the upper face of the platform 13 of the canopy, which recess may be considered as a continuation of the hole in the block when the same is positioned in its recess. The engagement of the inner end of the screw with the walls of the recess 41 prevents any sliding of the block 105 out of the recess so that it cannot become disengaged from the lugs 32 and is thus retained in position against movement in the direction of the sliding movement of the block to position it in its recess. Movement directly away from the canopy under the action of the insertion of an attachment plug is 110 prevented as before stated, by the overhanging lugs 32, and movement into the recess is limited by the engaging surfaces previously mentioned. The nut need not be fastened in the recess in the block 25 and it will 115 be seen that all of the means for retaining the insulation block in position are not dependent upon any parts being moulded into the insulation material. 120

It may be noted that certain conveniences 125 130

of manufacture result from the above arrangement of parts. The core blades which form the openings 14 are of such a length that their ends form the bottom walls 44 of the 5 overhanging lugs 32. Corresponding blades entering from the back of the canopy may form the inner walls 45 of the lugs and will continue down to form the widened portions 22 of the plug blade openings 14 so that both 10 of these sets of blades serve a double function and it is not necessary to provide any collapsible cores or similar structures for the moulding of the canopy. The convenience of this will be appreciated when the small 15 size of the parts is understood.

Having thus described the invention, what is claimed as new and desired to be secured by Letters Patent is:

1. In a wall bracket, in combination, a canopy of moulded insulating material, slots in 20 said canopy to receive attachment plug blades, a recess in the rear face of said canopy for each one of said slots, a contact freely resting in each recess, a block of insulating 25 material covering said recesses and a portion of said canopy overlying said block for the purpose described.

2. In an electric fixture, in combination, a canopy of moulded material, said canopy 30 having a slot to receive a blade of an attachment plug, said slot being enlarged into a contact holding recess at the back of said canopy, a contact loose in said recess, a block adapted to cover said recess and retain said 35 contact in position therein and means integral with said canopy engaging the side of said block opposite the contact.

3. In an electric fixture, in combination, a canopy of moulded material, said canopy 40 having a slot to receive the blade of an attachment plug, said slot being enlarged into a contact receiving recess at the back of said canopy, a contact loose in said recess, a block adapted to cover said recess and to retain 45 said contact in position, means on said canopy engaging said block to prevent movement thereof except in one direction and means on said block adapted to engage said canopy to prevent movement of said block 50 in that direction.

4. In an electric fixture, in combination, a canopy of moulded material having a slot from front to back thereof to receive an attachment plug blade, said slot being enlarged 55 near the back of said canopy to receive and hold a contact spring, a contact spring loose in said enlargement, a block of insulation covering the enlargement of said slot and retaining said contact in position, cooperating 60 surfaces on said block and canopy structure to hold said block in position against movement in all but one plane, said block having a hole therethrough at an angle to said plane, said canopy having an extension of said hole 65 and a fastening means in the hole in said

block and adapted to be projected into the hole in said canopy.

5. A separable joint for use between parts formed of frangible material comprising a 70 part having a groove, a second part having a portion adapted to fit in said groove and interlock against movement at an angle to the longitudinal axis of said groove, one of said parts having a hole therethrough at substantially right angles to said axis, a non-circular enlargement at the end of said hole adjacent said other part, a nut fitting in said enlargement and prevented from rotation by engaging the walls thereof, a screw passing through said hole and engaged in said nut, 75 said other part having a depression adapted to receive the end of said screw when projected beyond said nut to prevent relative movement of said parts in the direction of said axis.

6. A separable joint for use between parts formed of frangible material comprising a 80 part having a groove, a second part having a portion adapted to fit in said groove and interlock against movement at an angle to the longitudinal axis of said groove, one of said parts having a hole therethrough at substantially right angles to said axis, an enlargement at the end of said hole adjacent 85 said other part, a nut in said enlargement, a screw passing through said hole and engaged in said nut, said other part having a depression adapted to receive the end of said screw when projected beyond said nut to prevent relative movement of said parts in the direction of said axis.

7. In an electric fixture, in combination, a canopy having a portion of insulating material, said portion having a slot to receive the 90 blade of an attachment plug, a block adapted to close one end of said slot, a recess at that end of said slot, a contact spring held in said recess by said block and adapted to cooperate with said blade, and means on said portion to overhang said block to prevent 95 relative movement of the block in the direction of insertion of said blade.

In testimony whereof I hereunto affix my signature.

PETER E. BURNS.
